UNITED STATES PATENT OFFICE.

HAROLD O. HOLTE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL RELAY.

Application filed April 18, 1925. Serial No. 24,245.

My invention relates to electrical relays, and particularly to relays comprising a plurality of contacts and means for selectively operating the contacts.

5 I will describe several forms of electrical relays embodying my invention, and will then point out the novel features thereof in claims.

In the accompanying drawings, Fig. 1 is a 10 top view of one form of relay embodying my invention. Fig. 2 is a view showing in front elevation, the relay illustrated in Fig. 1. Fig. 3 is a detail view showing the pivot construction of the relay of Figs. 1 and 2. 15 Figs. 4 and 5 are a top view and a front view, respectively, of a modified form of relay also embodying my invention. Fig. 6 is a wiring diagram showing an arrangement of electrical circuits for controlling 20 the relay shown in Figs. 4 and 5. Figs. 7 and 8 are a top view and a front view, respectively, of still another form of relay embodying my invention. Fig. 9 is a wiring diagram showing an arrangement of circuits 25 for the windings of the relay illustrated in Figs. 7 and 8.

Similar reference characters refer to similar parts in each of the several views.

Referring first to Figs. 1, 2 and 3, the 30 relay comprises a base block A of magnetizable material. In the form here shown this base block is Y-shaped, and is provided with three upstanding cores 3, 4 and 5, of magnetizable material, one located at the extremity of each leg of the base block A. The cores 3, 4 and 5 are provided with windings 3^a, 4^a and 5^a, respectively, and it will therefore be seen that each core with its associated winding constitutes an electro-magnet. The upper ends of all of these 35 cores extend through a spacing member C of non-magnetizable material such as brass.

Upstanding from the center of the base block A is a core D comprising a permanent 40 magnet. This core D projects through the spacing member C and is somewhat longer than the cores 3, 4 and 5. The top of core D is provided with a socket 2 as best illustrated in Fig. 3. A substantially flat, Y-shaped plate B of magnetizable material is 45 provided, on its under side, with a pivot pin 1 (see Fig. 3) which enters the socket 2 in the top of core D. A stud 12 on member C enters a hole 13 in the plate B to

prevent rotation of the plate, but this stud 55 permits the plate to rock or tip freely on its pivot.

By properly proportioning the various parts, the plate B is so spaced above the upper ends of cores 3, 4, and 5 that when 60 the plate is tipped so that two of its legs abut against two adjacent cores, the remaining leg of the plate is raised. Flux from the permanent magnet core D serves to retain the plate B in the position to which it 65 was last moved until the plate is positively moved to a different position.

Three contacts 19, 20 and 21 are supported, by means not shown in the drawing, immediately above the three legs 9, 10 and 11, 70 respectively, of plate B. Each contact is so arranged that when the corresponding leg of plate B is depressed the contact is open, and when the corresponding leg is raised the contact is closed. 75

Current is at times supplied from a suitable source, such as a battery G, to the windings 3^a, 4^a and 5^a. The supply of this current is controlled by a circuit controller 14 which may, in turn, be operated in any suitable manner. 80

As shown in the drawing contact 14-17 is closed. Current is then supplied to winding 3^a, and the parts are so arranged that the flux created by this winding combines with 85 the flux supplied by the permanent magnet core D to repel leg 9 of plate B. The plate therefore rocks so that legs 10 and 11 engage the corresponding cores. With the plate B in this position, contact 19 is closed 90 but contacts 20 and 21 are open. Should the circuit controller 14 be opened, flux from the permanent magnet core D would hold the plate in the position shown in the drawing. 95

If now, contact 14-16 is closed, current is supplied to winding 5^a on core 5 and leg 11 of plate B is urged upwardly. Leg 10 remains down, and leg 9 also is forced down against the upper end of core 3. This motion 100 of the plate B closes contact 21 and opens contact 19 but contact 20 remains open.

When contact 14-15 is closed current is supplied to winding 4^a, and contact 20 is closed. Under these conditions contacts 19 105 and 21 are both open.

Referring now to Figs. 4, 5 and 6, the relay in the form here shown comprises a square

- base block A', from the four corners of which rise magnetizable cores 22, 23, 24 and 25. The tops of these cores are held in place by a non-magnetizable spacing member C'. 5 A centrally located core D' extends upwardly from base block A' through member C' and carried, by means of a pivot arrangement similar to that shown in Fig. 3, a square plate B' of magnetizable material. 10 As here shown, the under side of this plate is turned off to a very flat cone. A stud 12 on member C' enters a hole 13 in plate B' as in Fig. 1, to prevent rotation of the plate. The core D' is not a permanent magnet 15 but is provided with a winding 27 which is constantly supplied with energy from battery G. (See Fig. 6.) The core D' is also provided with a second winding 26 wound on the core in the opposite direction from 20 winding 27 and having the same number of ampere turns. It is therefore clear that when winding 26 is connected with battery G, the flux created therein neutralizes the flux created by winding 27. Each of the 25 cores 22, 23, 24 and 25 is provided with two windings designated by the same reference character as the associated core, with distinguishing exponents. The two windings on each core are wound on the core in opposite directions and the supply of current to these windings is controlled by circuit controller 14 as shown in Fig. 6. Without tracing the circuits in detail, it will be seen from the drawing that when 35 contact 14-15 is closed windings 22^a, 23^b and 26 are energized; when contact 14-16 is closed windings 23^a, 24^b and 26 are energized; when contact 14-17 is closed windings 24^a, 25^b and 26 are energized; and that 40 when contact 14-18 is closed windings 25^a, 22^b and 26 are energized. It is therefore clear that when any one of the contacts of circuit controller 14 is closed, current is supplied to windings on two adjacent cores, and 45 current is simultaneously supplied to winding 26 on core D' thereby neutralizing the flux from winding 27. The circuits are so arranged that when windings on two adjacent cores are thus energized, the fluxes created in the cores are of opposite direction. These fluxes therefore travel through the two cores, the plate B' and the base block A', thereby attracting the adjacent side of the plate B and drawing such side of the 50 plate downwardly. 55 Contacts 28, 29, 30 and 31 are located above the plate B', one on each side of the plate so that each such contact is normally open but is closed when the corresponding side of the plate is lifted as the plate is tipped about core D' by depression of the opposite side of the plate. 60 As shown in the drawing contact 14-17 is closed, thereby supplying current to windings 24^a, 25^b and 26. The flux created in 65 core D' by winding 27 is therefore neutralized, and the fluxes created in cores 24 and 25 by windings 24^a and 25^b depress the right hand side of plate B' as seen in Figs. 4 and 5. The left hand side of the plate is therefore 70 raised and contact 28 is closed. Contacts 29, 30 and 31 are all open. Should circuit controller 14 be opened, windings 24^a and 25^b would be de-energized, but winding 26 would also be de-energized, and the plate B' would 75 be held in the illustrated position by flux from winding 27. 80 If, now, contact 14-16 becomes closed, the holding flux created by winding 27 is neutralized, and the flux created in cores 23 and 24 by current through windings 23^a and 24^b draws downwardly on plate B' at the upper edge as seen in Fig. 4. This upper edge is 85 swung toward the cores 23 and 24, and the opposite edge is tipped up to close contact 31. Under these conditions contacts 28, 29 and 30 are all open. 90 The operation of the relay when contact 14-15 or contact 14-18 is closed, will be apparent from the foregoing. 95 In the modification shown in Figs. 7, 8 and 9, the relay comprises a square base plate A², having four cores 22, 23, 24 and 25 upstanding from the corners thereof, and a central core D². These cores are held in spaced relation adjacent their tops by a non-magnetic spacing member C². A square plate B² is pivotally supported in the top of core D² as in Fig. 3. The four contacts 28, 29, 30 and 31 are arranged, one at each corner 100 of the plate B² over the cores 22, 23, 24, and 25, respectively. 105 The spacing member C² carries four upstanding studs 32, 33, 34 and 36, one located midway between each two adjacent corner cores. These studs are of such height that when one corner of the plate B² is depressed, as for example the right hand corner in the drawing, the lower side of the plate abuts against the two adjacent studs, in this case 110 studs 33 and 34. It will therefore be clear that each pair of studs, with the center pivot of the plate, define a fixed position for the plate B² into which the plate is moved when the winding for the core between such studs 115 is energized. 115 Core D² is provided with two windings 26 and 27 similar to those on core D' of Figs. 4, 5 and 6. Each of the remaining cores is provided, as shown in Fig. 9, with a single winding designated by the same reference character as that applied to the core, with the exponent *a*. The supply of current to these windings is controlled by circuit controller 14 as shown in Fig. 9. The circuits 120 will be clearly understood without further explanation. 125 As shown in the drawing contact 14-18 is closed, energizing windings 24^a and 26. Flux from winding 27 is therefore neutral- 130

ized, and flux from winding 24^a draws the right hand corner of the plate B² downwardly against studs 33 and 34. With plate B² in this position contact 28 is closed, and 5 contacts 29, 30 and 31 are all open.

Similarly, should the winding on any of the other corner cores be energized the corresponding corner would be depressed to engage the adjacent studs, and the opposite 10 corner would be raised to close the associated contact.

If circuit controller 14 is open flux from winding 27 serves to hold the plate B² in the position to which it was last moved.

15 The upper end of stud 36 is of reduced diameter and projects into a hole 37 in plate B² to prevent rotation of the plate about its pivot in core D².

The various contacts controlled by the 20 relays may be utilized to control other apparatus in any suitable manner. It should be pointed out that while I have here illustrated the contacts as normally open and each closed by proper operation, the relay 25 might equally well be arranged to open normally closed contacts.

Relays embodying my invention are particularly suitable for, though in no way limited to, use in railway traffic controlling systems. In systems of this character circuit 30 controller 14 will usually be arranged to respond to changes in traffic conditions.

Although I have herein shown and described only a few forms of electrical relays embodying my invention, it is understood that various changes and modifications may be made therein within the scope of the appended claims without departing from the spirit and scope of my invention.

40 Having thus described my invention, what I claim is:

1. A relay comprising a plate pivotally supported at a point, operating means for moving said plate into a plurality of planes 45 intersecting in different lines through said point, and a plurality of contacts one corresponding to each said plane and operated when said plate occupies such plane.

2. A relay comprising a magnetizable base block, a constantly magnetized core up- 50 standing from said block, a plurality of other cores upstanding from said block and spaced from said constantly magnetized core and from each other, a plate of magnetizable material pivotally supported on said constantly magnetized core and extending over the ends of said other cores, means for creating a magnetic flux in selected ones of said other cores, and contact mechanism controlled in accordance with the position of 55 said plate.

3. A relay comprising a plate capable of 60 assuming a plurality of positions, means for moving said plate to any one of said positions, other means for retaining said plate

in the position to which it was last moved, and contact mechanism controlled in accordance with the position occupied by said plate.

4. A relay comprising a plate capable of 70 assuming a plurality of positions, a plurality of magnets one for moving said plate to each such position, another magnet for retaining said plate in the position to which it was last moved, and contact mechanism controlled in accordance with the position 75 of said plate.

5. A relay comprising a plate capable of 80 assuming a plurality of positions, a plurality of magnets one for moving said plate to each such position, another magnet for retaining said plate in the position to which it was last moved, and a plurality of contacts one corresponding to each said position of the plate and arranged to be closed when the plate occupies the corresponding 85 position.

6. A relay comprising a Y-shaped base block, a constantly magnetized core upstanding from the center of said block, three other magnetizable cores one upstanding from the 90 free end of each leg of said block, a plate loosely pivoted on the top of said constantly magnetizable core and extending over but spaced from the upper ends of said other cores, a winding for each of said other cores, means for supplying current to any selected one of said windings to move said plate upwardly adjacent such winding, and three contacts above said plate one adjacent each of said other cores, each said contact arranged to be closed by said plate when the adjacent winding is supplied with current.

7. A relay comprising a plurality of spaced parallel magnetizable cores, a magnetizable base block for connecting the cores together 100 at one end of the cores, a constantly magnetized core attached to said block and extending parallel with said first mentioned cores, a magnetizable plate supported by said constantly magnetized core and extending 110 adjacent the free ends of the remaining cores, means for actuating said plate by creating flux in a selected one of said remaining cores, and contact mechanism controlled by said plate.

8. A relay comprising a plurality of spaced 115 magnets each comprising a core provided with a winding, a plate pivotally supported adjacent the ends of said cores, a stud fixed with respect to said cores and entering a hole in said plate to prevent rotation of said plate but to permit oscillation of the plate about its pivot, means for selectively energizing said windings, and contact mechanism controlled by said plate.

9. A relay comprising a plate supported 120 adjacent its center at a pivotal point, a plurality of magnets spaced symmetrically about said pivotal point, a plurality of studs symmetrically disposed about said pivotal point,

one such stud being located between each two said magnets, means for energizing a selected one of said magnets to move said plate into engagement with the two studs adjacent such 5 energized magnet, and contact mechanism controlled by said plate.

10. A relay comprising a central core and a plurality of other cores disposed parallel therewith and symmetrically thereabout, a 10 plate of magnetizable material pivotally supported on said central core and extending over said other cores, a winding on each said core, means for energizing the winding for any selected one of said cores and for simultaneously 15 energizing the winding for said central core, and contact mechanism controlled by said plate.

11. A relay comprising a central core and

a plurality of other cores disposed parallel therewith and symmetrically thereabout, a 20 plate of magnetizable material pivotally supported on said central core and extending over said other cores, a winding one each said core, means for energizing the winding for any selected one of said cores and for simultaneously 25 energizing the winding for said central core, a second winding for said central core for creating a flux in opposition to the flux created in such core by the other winding thereon, means for constantly energizing said second winding, and contact mechanism controlled by said plate.

In testimony whereof I affix my signature.

HAROLD O. HOLTE.
